OF D 20,320

D20320

UNITED STATES PATENT OFFICE.

HENRY CLAY BASCOM, OF LANSINGBURG, AND FRANCIS RITCHIE, OF TROY,
NEW YORK.

DESIGN FOR A HEATING-STOVE.

SPECIFICATION forming part of Design No. 20,320, dated November 18, 1890.

Application filed September 29, 1890. Serial No. 366,563. Term of patent 7 years.

To all whom it may concern:

- Be it known that we, HENRY CLAY BASCOM and FRANCIS RITCHIE, citizens of the United States, the said BASCOM residing at 5 the village of Lansingburg, county of Rensselaer, and State of New York, and the said RITCHIE at the city of Troy, said State and county, have invented and produced a new and original Design for Heating-Stoves, of 10 which the following is a specification, reference being had to the accompanying drawing, forming a part thereof, and consisting of a single figure, affording a view in perspective of our new design.
- 15 The characteristic features of our design are the corner columns connected by the horizontal bands, the small branches, the foliated scroll, the transversely-arranged ribs, the flambeau and scrolls, and the grotesque 20 mask with foliated outlines, all as hereinafter described and particularly pointed out.
- The legs A of the stove have at their upper ends a plain horizontal border-band with a scroll A¹, branching from the lower edge near 25 the ends of the band, and a front ornament composed of foliated scrolls touching said band, and at their lower ends a plain border-band wider than the upper border-band and made continuous with the ribs on the vertical 30 edges of the leg.
- The base A³ has a plain upper surface and a plain inclined edge-wall A⁴, rounded and fluted at the front corners.
- Depending from the base on the front side 35 of the stove is an ornamented panel A⁵, having its upper edge bordered by a straight horizontal rib terminating near the stove leg socket and its lower edge outlined by a curved rib provided with scroll terminals and 40 branches, two of which terminals are immediately under the upper rib near the ends thereof, and a patera A⁶, near the middle of the panel at the junction of two scroll branches.
- 45 Rising from the stove-base are the front corner columns B. The base of the columns comprises the concave moldings or plinth B¹, beneath a rectangular panel B², with a horizontal egg-molding B³ between the panel and 50 plinth, and a similar egg-molding B⁴ above
- the panel. The lower end of the shaft is provided with an ornamental figure consisting of foliated scrolls. The shaft is decorated from the ornamental figure to the astragal with a series of sigmoidal ribs, the several 55 ribs running transversely of the shaft. Above the beaded astragal B⁵ is the capital B⁶, having foliated ornaments, and an ornamental figure consisting of a flambeau B⁷ between two scrolls. The capitals support the stove- 60 top having plain edge-walls C.
- Beneath the stove-top and between the column-capitals is a horizontal band C', connecting the columns and decorated with a foliated vine-like rib having scroll branches. 65
- Between the corner columns on the stove-front are two sets of rectangular doors D and D', one above the other. Each door is provided on its front with a rectangular border-band of uniform width on each of the four 70 sides, inclosing an ornamental figure, consisting of a grotesque mask having foliated outlines. The upper pair of doors is separated from the lower pair by the horizontal band D², which connects the columns intermediately of their ends, and is decorated by a foliated vine-like rib having scroll branches. 75
- What I claim as new is—
1. The ornamental design for a heating-stove herein shown and described, consisting 80 of a pair of front corner columns rising from the base to the top of the stove, connected at their upper ends and at points intermediately of the ends by a horizontal band, and two sets of doors on the front of the stove, separated from each other by the lower column-connecting band.
  2. In a design for a stove, the design for a stove-leg herein shown and described, consisting of a plain horizontal border-band with 85 a scroll branch near each end and on the under side thereof, and a front ornament composed of foliated scrolls on the upper part of the leg touching said band, and a plain border-band wider than the upper border-band on the lower end of the leg and continuous with a rib on the vertical edges of the same.
  3. In a design for a stove, the design for the stove-base herein shown and described, 90

OVER

consisting of the plain upper surface, plain inclined edge-wall with rounded and fluted front corners, and an ornamental panel depending from the front edge of the base having its upper edge bordered by a straight horizontal rib terminating near and in the same plane with the stove-leg socket and its lower edge outlined by a curved rib provided with scroll terminals and branches, two of said terminals being located immediately under the upper rib, the middle part of the panel having a patera at the junction of two scroll branches.

4. In a design for a stove, the ornamental design for a corner column herein shown and described, consisting of a base comprising a concave plinth beneath a rectangular panel with an egg-molding between the panel and plinth and an egg-molding above the panel, a shaft having on its lower end an ornamen-

tal figure composed of foliated scrolls and decorated from such figure to the upper end with a series of sigmoidal ribs, the several ribs running transversely of the shaft, a beaded astragal, a capital having foliated ornaments, and an ornamental figure consisting of a flambeau between two scrolls.

5. In a design for a stove, the design for a stove-door herein shown and described, consisting of a plain rectangular border-band of uniform width on each of the four sides enclosing an ornamental figure consisting of a grotesque mask having foliated outlines.

In testimony whereof we have hereunto set our hands this 24th day of September, 1890.

II. CLAY BASCOM.
FRANCIS RITCHIE.
